UNITED STATES PATENT OFFICE.

JAMES C. ANDERSON, OF RUTHERFORD, NEW JERSEY, ASSIGNOR TO VARLEY DUPLEX MAGNET COMPANY, A CORPORATION OF NEW JERSEY.

CIRCUIT BREAKER AND CONTROLLER.

1,400,929.

Specification of Letters Patent. Patented Dec. 20, 1921.

Application filed August 22, 1919. Serial No. 319,092.

To all whom it may concern:

Be it known that I, JAMES C. ANDERSON, a citizen of the United States, residing at Rutherford, in the county of Bergen and 5 State of New Jersey, have invented certain new and useful Improvements in Circuit Breakers and Controllers, of which the following is a full, clear, and exact description.

My invention relates to the breaker systems for the ignition circuits of internal combustion engines and one useful application of my invention is to the ignition circuits of automobile engines. More particularly my invention has to do with the occurrence of the spark for ignition relative to the cycle of the engine, and also to the regulation of the dwell, as it is called, of the electrical contacts at various engine speeds, that is, the relative duration of the periods of open 10 and closed contact position.

As is well known, the relative instant of firing should be advanced as the speed of the engine increases, and this is commonly effected by changing the relation of the cam 15 and cam follower which controls the movable contact in the breaker system, the adjustment being either manual or automatic or both. In some cases the cam is adjusted on its axis, and in others the breaker system is adjusted 20 about the cam, the adjustment being concentric with the cam, that is, about the axis of the cam as a center.

The duration of dwell or closed position of the breaker contacts must be for such a 25 period as will enable the energy in the primary coil to rise to the critical value required to produce a spark of the necessary intensity. This period manifestly bears a different relation to the period of open contact position 30 at different engine speeds, being relatively longer at high speeds than at low speeds. Various expedients have heretofore been employed to relatively prolong the dwell referred to as the speed of the engine increases, 35 which expedients have entailed more or less complicated mechanism commonly operated and controlled independently of the mechanism for adjusting the occurrence of the spark.

50 An object of my invention is to provide simple and practical means for maintaining the period of electrical dwell substantially constant at varying engine speeds. Another object is to coordinate the regulation of the 55 occurrence of the spark and of the period of

dwell and thereby effect both regulations by a single operation. Another object is to combine with the automatic means for effecting the double regulation, manual means for adding to or subtracting from the automatic 60 spark adjustment, the operation of which will not interfere with the automatic mechanism. Another object is to provide simple and reliable means which can be conveniently associated with means for accomplishing the above objects and which will assure that the primary circuit will be open when the engine is not running, thereby conserving the current supply. Still other objects and advantages of my invention will appear 65 from the following description.

My invention will be readily comprehended by reference to the diagrams constituting Figures 1 to 6 of the drawings.

Fig. 1 is a diagram representing a symmetrically lobed cam.

Fig. 2 is an enlarged development of two lobes of the cam represented in Fig. 1 and illustrating the effect of moving the working face of the cam follower radially outwardly.

Fig. 3 is a similar development illustrating the effect of moving the working face of the follower substantially parallel to the leading face of the cam lobe.

Fig. 4 is a similar development illustrating the effect of moving the working face of the follower diagonally outwardly as contemplated by my invention.

Fig. 5 is a diagram showing a development of a lobe of a cam which embodies my invention and illustrating the comparison between such a cam lobe and that of the symmetrically lobed cam of Fig. 1.

Fig. 6 is an enlarged diagram of two lobes of a cam embodying the preferred form of my invention.

Fig. 7 is a central vertical section on line 7-7 of Fig. 8 of a breaker and controller mechanism embodying my invention.

Fig. 8 is a plan of the same with the cover removed.

Fig. 9 is a transverse section on line 9-9 of Fig. 7.

Fig. 10 is a view similar to Fig. 9 with the governor ring in horizontal position.

Fig. 11 is a sectional detail in elevation on line 11-11 of Fig. 8.

Fig. 12 is an enlarged diagrammatic plan of the cam and breaker system.

It is understood that the cam follower

serves also as a circuit breaking and closing arm, and that contact of the cam follower with the leading face of the cam lobe breaks the electrical circuit, while the retreat 5 of the follower from the trailing face of the cam lobe establishes the electrical circuit. The angular distance between the break and make positions of the cam follower constitutes the dwell of the follower 10 on the cam surface, and the difference between that distance and the angular distance between the centers of the cam lobes, that is, the angular distance between the make and break positions of the follower, constitutes 15 the dwell of the electrical circuit.

Ordinarily, with a given lobed cam, moving the working face of the follower in an arc concentric with the axis of the cam merely varies the angular position at which 20 electrical contact is made or broken, that is, the angular advance or relative occurrence of sparking, without affecting the duration of contact or dwell.

In Fig. 1 is represented a symmetrically lobed cam, while Figs. 2, 3 and 4 are enlarged developments of two lobes of the cam represented in Fig. 1. With such a cam, moving the working face of the follower outwardly, substantially radially, 30 across the path of the cam lobes, increases the duration of electrical contact or dwell, but retards the spark occurring at the breaking of the circuit. This is clear from Fig. 2 in which the two positions of the follower are indicated in dotted lines when moved in the direction of the arrow *a*.

If the working face of the follower be moved diagonally outward, substantially parallel to the leading face of the cam lobe, 40 as represented by the arrow *b* in Fig. 3, the duration of electrical dwell is prolonged, but the occurrence of sparking remains constant or nearly so. This is clear from Fig. 3, where it appears that the cam follower 45 will be struck by the leading face of the cam lobe at the same angular position in both positions of the follower.

My invention comprehends the relative movement of the working face of the cam follower diagonally outward to effect a regulation of the duration of the period of electrical dwell at varying engine speeds. In its preferred adaptation my invention comprehends the relative movement of the cam follower substantially along a line which is 50 the resultant of the two components of movement to effect the regulation of the occurrence of spark and of the duration of dwell of the electrical circuit, thereby effecting the two regulations by a single movement. Since the movement to change the occurrence of sparking is in an arc concentric with the cam periphery, and the movement to change the duration of electrical 60 dwell is outward along a line substantially 65

parallel to the leading face of the cam lobe (Fig. 3) it follows that the resultant of the two must be along a diagonal line lying between the leading face of the cam lobe and the cam periphery indicated by the dotted line *P*, that is, at an angle to the tangent to the periphery, which in the development coincides with the periphery, less than that of the leading face of the cam lobe. This appears clearly from Fig. 4 in which the arrow *c* indicates the relative path of movement of the follower, and the relative position of the lobe *A* is indicated by dotted lines at the instant of breaking the contact in the advanced position of the cam follower.

To effect this movement I preferably mount the breaker system including the cam follower upon a pivot eccentric to the axis of the cam, the pivotal axis being located 85 in a line substantially normal to and bisecting the line connecting the points of contact of the cam follower with the cam at the two extremes of adjustment of the cam follower. As the speed of the engine increases 90 the breaker system is rotated on its pivot and the working face of the cam follower moves substantially along the line of the arrow *c*. In this way at low engine speeds with retarded spark a minimum of electrical 95 contact is obtained, thereby conserving the supply of electrical energy; and at high engine speeds the spark occurs earlier to fully ignite the charge in the engine cylinders, and electrical contact or dwell is maintained 100 for a greater angular distance on the shaft carrying the cam, whereby at higher engine speeds the dwell is not unduly shortened.

In order to obtain greater precision to the occurrence of the spark, my invention also 105 comprehends a cam in which the leading face of its lobes is at a greater angle to the tangent to the cam periphery than is the trailing face, from which it will be seen that among other advantages, the breaking 110 of the electrical circuit is accomplished with greater rapidity, giving a spark of greater intensity. This will be apparent from the diagram of Fig. 5, from which it will be also seen that the variation in the duration of dwell for a given relative movement of the cam and cam follower, is considerably 115 greater than the variation in the occurrence of sparking.

Fig. 6 is a representation of two lobes of 120 a cam having a profile substantially that preferred by me, although the angles are somewhat exaggerated and the radial distances are enlarged to more clearly show the path of the cam follower. The two extremes of adjustment of the cam follower are indicated by the two semi-circles marked *f*, one in full lines and one in dotted lines, the axis of movement being on the line *x-y* which is normal to and bisects the centers 125 130

of the work face of the follower f in the two positions. I preferably pivot the breaker system on a point in the line $x-y$ which is nearest the axis of the cam, as the point C, for I thereby obtain good proportionality throughout the entire range of adjustment, and I also find this desirable, in contradistinction to pivoting at a point outside the cam face, where automatic means for effecting and controlling the adjustment is desirable, such, for example, as the illustrated embodiment of my invention, in which a centrifugal governor operated by the engine is used to shift a turntable as the engine speed varies. It is manifest that if the system be pivoted about the point C' as a center, the follower will be shifted between the positions indicated by f and f' , and that the movement will affect only the duration of electrical dwell and not the angular advance. By swinging about the point C as a center it will be observed that an angular adjustment of substantially 10° effects a change in the period of dwell of substantially 25° in a six lobed cam, the angular distance between the two positions f and f' of the follower being the duration of dwell, which is shown as 15° in the innermost adjustment and 40° in the outermost adjustment. f^3 is an imaginary position and represents merely the concentric component of the movement, that is the component which determines the angular advance or the adjustment of the occurrence of the spark. This component it will be noted is 10° . It will be understood that these figures are only illustrative and approximate. While for the purpose of illustration I have arbitrarily utilized a central portion of the path of the cam lobes in which the adjustment is made, it will be understood that the zone of adjustment may be in any portion of the cam path, and in practice the apex of the cam lobe may be cut off just beyond the outer position of adjustment of the follower, the cam faces being extended beyond the outer position only enough to insure sufficient opening of the breaker contacts.

Figs. 7 to 12 illustrate one practicable embodiment of my invention.

The shaft 1, which carries the cam 2 on its upper end, is driven from the engine and is also coupled to drive a distributor shaft 3. The housing 4, which is constructed in two separable parts, is provided in its top wall with a central integral upright sleeve portion 5 which affords a bearing for the upper end of the shaft 1. Surrounding the sleeve 5 is a plate 6 which bears on top of the top wall of the housing 4 and has an upwardly extending hub portion 7 bearing upon the external surface of the sleeve 5, the external cylindrical surface of the hub portion being eccentric to the axis of the shaft 1 and having its center substantially in the location of the center C in Fig. 6. Surrounding the hub portion 7 is a turn table 8 or adjustable support for the breaker system, which has a concentric hub portion 9 bearing around the eccentric external surface of the hub 7. It is manifest, therefore, that if the turn table be rotated about the eccentric hub, the breaker system and cam follower will be eccentrically adjusted about the cam substantially along the direction of the arrow c in Fig. 4, while if the plate 6 be angularly rotated, the adjustment of the breaker system will be in an arc coaxial with the cam.

To adjust the turn table about the eccentric bearing, automatic speed controlled means are provided. The turn table is resiliently biased in a clock wise direction as viewed in Fig. 8, by a thrust spring 10 which acts upon a radial extension 11 on the turn table through the medium of a thrust rod 12 which is slidable in a post 13 on the plate 6 and bears with a pointed end in a conical socket in the extension 11, thereby minimizing friction. A lug on a post 14 on the plate 6 serves as a limiting stop for the extension 11.

To adjust the breaker system in a counter clock wise direction against the tension of the spring 10 mechanism is employed which is operated by a centrifugal governor. The specific governor employed for the purpose of illustration is a ring 15 which is carried by the shaft 1 and when at rest occupies the inclined position shown in Figs. 7 and 9, and tends under centrifugal force to assume the horizontal position shown in Fig. 10. The ring 15 is carried by a sleeve 16 which is secured to the shaft 1 and is provided with two opposite extensions 17 which afford bearings for the pivots 18 of the ring 15. The sleeve 16 and shaft 1 are slotted to accommodate a link 19 which is pivoted in ears 20 on the sleeve and bears with its free end upon a horizontal pin 21 carried by the governor ring 15 on the side of the shaft opposite the ears 20. Resting upon the top of the link 19 is the lower end of a rod 22 which is vertically slidable in an axial bore in the upper end of the shaft 1, and protrudes slightly beyond the end of the shaft. This rod 22 actuates a bell crank lever 23 which is pivoted on a horizontal axis in the post 14 and a companion post 24 on the plate 6. One arm of the bell crank lever overhangs the axis of the shaft 1 and bears upon the top rounded end of the axial rod 22. The other arm of the bell crank engages the radial extension 11 on the turn table on the side opposite the thrust spring 10 through the agency of the rod 25 which is interposed between the arm of the bell crank and the

extension 11 and is pointed at both ends and engages in conical sockets to minimize friction.

It is manifest that as the rod 22 is elevated by the governor ring, its movement will be transmitted to the turn table through the bell crank 23 and the rod 25, and the turn table will be correspondingly rotated in a counter clock wise direction against the tension of the spring 10. This rotative movement of the turn table is governed by the engine speed and serves both to advance the spark and prolong the electrical dwell. In the illustrated breaker system the cam follower 26 which carries the movable contact is of the non-pivoted type, being carried by a flat spring which flexes to afford the requisite movement to the breaker arm. The elevation of the cam follower breaks the contact at point 27, and the resiliency of the flat spring causes the contact to close as the cam follower rides off the trailing face of the cam lobe.

In Fig. 12 the breaker system is shown in full lines in the angular position of substantially greatest retard, while it is shown in dotted lines in the position of substantially greatest advance, the cam 2 being correspondingly shown in full and dotted lines in the two positions which it occupies at the instant of engaging the cam follower in the two respective positions. As pointed out above the movement of the cam follower from the position shown in full lines to that shown in dotted lines serves both to advance the spark and prolong the relative period of electrical dwell, while the movement of the cam follower in the opposite direction under the influence of the spring 10 effects the opposite adjustment to the spark and electrical dwell.

As above explained conditions will sometimes require that the angular adjustment of the spring which is automatically effected through the centrifugal governor be added to or subtracted from in order to obtain the best results. In the construction shown this may be manually done by rotating the plate 6 and its eccentric hub 7. For this purpose the plate 6 is provided with an adjusting arm 28 which is connected by a link 29 to any suitable place for manual manipulation, such as the steering post. Since the internal bearing surface of the hub 7 is concentric with the shaft 1, the adjustment of the plate 6 causes the corresponding angular adjustment of the cam follower 26 in an arc axial with that of the cam 2, which adjustment affects only the occurrence of the spark. It will be noted that this manual adjustment cannot result in injury to the automatic adjusting mechanism. This is due to the fact that the connection between the bell crank 23 and the rod 22 is only a point of bearing or engagement, which

point is on the axis of rotation of the bell crank when the manual adjustment is operated. There can therefore be no overhauling or breaking of the mechanism for effecting the automatic control.

In the illustrated construction the automatic mechanism also controls a contact in the battery circuit and operates to open the contact when the engine is at rest, and to close it when the engine is running. The depending arm of the bell crank 23 bears at its lower end against a flat spring 30 which carries the movable contact 31. While the arm of the bell crank is retracted by the spring 10, it holds the contact open as shown in Figs. 7 and 8, and as soon as the engine starts and the shaft 1 is rotated the governor ring operates to rock the bell crank clear of the spring arm 30 and permits the contact 31 to close. The governor is preferably sufficiently sensitive to close the contact 31 at the number of revolutions per minute imparted to the governor by the cranking motor, although, in order to get a closed primary circuit while the engine is being cranked, a branch may be provided around the contact 31 in which there is a suitably manually controlled switch.

While the lobes of the cam are shown and described as having a straight or plane leading face, it will be understood that if curved faces are employed, the description will apply to the tangent to such curves.

My invention is in no wise limited to the particular construction which has been chosen for the purpose of illustration, but may be variously otherwise employed without departing from the scope of the appended claims. For instance, as above suggested, it is obvious that with any suitable cam the ordinary governor construction may be employed to effect the adjustment of the occurrence of the spark, and the breaker system may be mounted for relative outward movement, such as radial, to regulate the duration of electrical dwell, as indicated in Fig. 2; and other obvious modifications may be made within the spirit of my invention.

I claim:

1. For the ignition circuit of an internal combustion engine, a rotative shaft connected to be driven by the engine, a breaker cam carried by the shaft, a bearing sleeve for the shaft having a concentric external bearing surface, a bearing member adjustably bearing about the sleeve and having an eccentric external bearing surface, a breaker system including a cam follower controlled by the cam, and an angularly adjustable support for the breaker system bearing about the external surface of the bearing member.

2. For the ignition circuit of an internal combustion engine, a rotative shaft connected to be driven by the engine, a breaker cam carried by the shaft, a bearing sleeve

- for the shaft having a concentric external bearing surface, a bearing member adjustably bearing about the sleeve and having an eccentric external bearing surface, a breaker system including a cam follower controlled by the cam, an angularly adjustable support for the breaker system bearing about the external surface of the bearing member, and a centrifugal governor rotative with the shaft and arranged to control the angular position of the support. 5
3. For the ignition circuit of internal combustion engines, the combination of a breaker cam, a cam follower adapted to open and close an ignition circuit and mounted for adjustment relative to the cam, a lever for adjusting the cam follower, a movable contact member in an ignition circuit controlled by the lever, and a centrifuge rotated by the engine and arranged to control the lever and operative in its innermost position to hold the lever in the open circuit position of the contact member. 10
4. For the ignition circuit of an internal combustion engine including a pair of breaker contacts, a shaft connected to be rotated by the engine, a movable contact closer independent of the breaker contacts and having a bias to closed position, a bell crank lever arranged to control the contact closer and biased to normally hold the contact closer open, and a centrifugal governor rotatable with the shaft and operative to move the bell crank lever against its bias and permit the contact to close and thereafter to continuously hold the bell crank lever clear of the contact closer. 15
5. For the ignition circuit of an internal combustion engine, a rotative shaft connected to be driven by the engine, a breaker cam carried by the shaft, a breaker system including a cam follower controlled by the cam, an angularly adjustable support for the breaker system, a movable contact closer in the circuit independent of the breaker system, and a centrifugal governor rotatable with the shaft and arranged to control both the contact closer and the adjustable support. 20
6. For the ignition circuit of an internal combustion engine, a rotative shaft connected to be driven by the engine, a breaker cam carried by the shaft, a breaker system including a cam follower controlled by the cam, an angularly adjustable support for the breaker system, resilient means tending to hold the support in one angular position, a movable contact closer in the circuit independent of the breaker system, a pivotal bell crank lever arranged to oppose the resilient means and controlling the contact closer, and a centrifugal governor rotatable with the shaft and having operative connection with the bell crank lever. 25
7. For the ignition circuit of an internal combustion engine, a shaft connected to be driven by the engine, a lobed breaker cam carried by the shaft and having the leading face of the lobe at a more acute angle to the radial plane including the line of intersection of the leading and trailing faces than is the trailing face, a breaker system comprising a supporting plate pivoted eccentrically to the axis of the cam, a pair of contacts carried by the plate, one of which is movable to open and close the ignition circuit, a cam follower controlling the movable contact, the pivoted axis of the supporting plate being so located relative to the axis of the cam that pivotal movement of the plate causes the cam follower to describe a path eccentric to the axis of the cam having both a radial and a circumferential component, and means responsive to the speed of the engine for controlling the angular adjustment of the supporting plate about its pivotal axis. 30
8. For the ignition circuit of an internal combustion engine, a shaft connected to be driven by the engine, a lobed breaker cam carried by the shaft and having the leading face of the lobe at a more acute angle to the radial plane including the line of intersection of the leading and trailing faces than is the trailing face, a breaker system comprising a supporting plate pivoted eccentrically to the axis of the cam, a pair of contacts carried by the plate, one of which is movable to open and close the ignition circuit, a cam follower controlling the movable contact, the pivoted axis of the supporting plate being so located relative to the axis of the cam that pivotal movement of the plate causes the cam follower to describe a path eccentric to the axis of the cam having both a radial and a circumferential component, and a centrifugal governor rotatable with the shaft and operatively connected to the supporting plate to control the angular adjustment of the supporting plate about its pivotal axis. 35
9. For the ignition circuit of an internal combustion engine, a shaft connected to be driven by the engine, a lobed breaker cam carried by the shaft and having the leading face of the lobe at a more acute angle to the radial plane including the line of intersection of the leading and trailing faces than is the trailing face, a breaker system comprising a supporting plate pivoted eccentrically to the axis of the cam, a pair of contacts carried by the plate, one of which is movable to open and close the ignition circuit, a cam follower controlling the movable contact, the pivoted axis of the supporting plate being so located relative to the axis of the cam that pivotal movement of the plate causes the cam follower to describe a path eccentric to the axis of the cam having both a radial and a circumferential component, 40

6
a movable contact closer, and a centrifugal governor rotatable with the shaft and arranged in control of both the contact closer and the angular adjustment of the supporting plate about its pivotal axis.

10. For the ignition circuit of an internal combustion engine, a rotative cam, a breaker system including a cam follower adjustable angularly relative to the cam upon an axis eccentric to the cam, adjustable mechanism for the breaker system mounted for coaxial adjustment relative to the cam, and speed controlled means for actuating the adjusting mechanism having an operative connection therewith coaxial with the cam.

11. For the ignition circuit of an internal combustion engine, a rotative cam, a breaker

system including a cam follower mounted for angular adjustment both eccentrically and concentrically of the cam, and automatic speed-controlled means for effecting the eccentric adjustment.

12. For the ignition circuit of an internal combustion engine, a rotative cam, a breaker system including a cam follower mounted for angular adjustment both eccentrically and concentrically of the cam, automatic speed-controlled means for effecting the eccentric adjustment, and manually operative means for effecting the concentric adjustment.

In witness whereof, I subscribe my signature.

JAMES C. ANDERSON.
